FIG. 10

FIGURE 1 is a front perspective view taken from the right side of a water closet embodying my new design;

FIGURE 2 is a front elevational view thereof;

FIGURE 3 is a rear elevational view thereof;

FIGURE 4 is a top plan view thereof;

FIGURE 5 is an elevational view taken from the left side thereof;

FIGURE 6 is a front perspective view taken from the right side of a modified form of said water closet;

FIGURE 7 is a front elevational view thereof;

FIGURE 8 is a rear elevational view thereof;

FIGURE 9 is a top plan view thereof; and FIGURE 10 is an elevational view taken from the left side thereof.

This is a continuation of my prior co-pending applications Serial Nos. D. 59,054 and D. 59,055, both filed on January 15, 1960 and now abandoned.

I claim:

The ornamental design for a water closet, as shown and described.
